Western, LLP

(57) **CLAIM**

The ornamental design for the gripless non-lethal personal
defense weapon, as shown.

DESCRIPTION

FIG. 1 is a perspective view of the gripless non-lethal
personal-defense weapon in a closed position showing a first
embodiment in accordance with our invention;

FIG. 2 is a perspective view thereof in an open position;

FIG. 3 is a top plan view thereof in the closed position;

FIG. 4 is a bottom plan view thereof;

FIG. 5 is a left side elevation view thereof, the right side
elevation view being a mirror image;

FIG. 6 is a top plan view thereof in the open position;

FIG. 7 is a front elevation view thereof; and

FIG. 8 is a rear elevation view thereof.

FIG. 9 is a top plan view of the gripless non-lethal personal-
defense weapon showing a second embodiment in accord-
ance with our invention;

FIG. 10 is a bottom plan view thereof;

FIG. 11 is a right side elevation view thereof;

FIG. 12 is a left side elevation view thereof;

FIG. 13 is a front elevation view thereof; and,

FIG. 14 is a rear elevation view thereof.

The dashed lines shown in FIGS. 10-13 form no part of the
claimed design.

1 Claim, 7 Drawing Sheets
